UNITED STATES PATENT OFFICE.

WILLIAM E. ELAM, OF WASHINGTON, DISTRICT OF COLUMBIA.

DRAWING APPARATUS.

Application filed May 7, 1926. Serial No. 107,453.

My present invention has reference to a drawing apparatus and has for its primary object a device of this character which will, to a great extent, eliminate the employment 5 of the ordinary rule, dividers, or other measuring instruments, required in the making of scaled straight line drawings, with the result that with my improvement drawings of this character may be more accurately executed 10 in a more expeditious manner and with less strain on the mind and on the eyes of the draftsman.

This object I attain by providing two cooperating drafting plates; one a 45 degree 15 right angle triangle and the other a 60—30 degree triangle.

In the accompanying drawings:

Figure 1 is a plan view of a 45 degree right angle triangle in accordance with this invention.

Figure 2 is a similar view of a 60—30 degree triangle provided with the fingers and guards.

Figure 3 is a view, in elevation, of one side 25 of the triangle illustrated in Figure 1.

Figure 4 is a fragmentary plan view of both of the triangles in cooperating position.

Figure 5 is a fragmentary plan view to illustrate the adjustable finger employed.

Figure 6 is an elevation of part of the triangle illustrated in Figure 2, showing the finger and the guards.

Figure 7 is a plan view of a form of plate which may be employed.

On the upper or outer face of the triangle 35 10, in close proximity and parallel to the short sides 12 and 13 thereof, there are secured ribs 14, preferably of metal and rectangular in cross section. These ribs are 40 provided with upright transverse notches 16 that form graduations.

Some of these notches are one inch apart to form one inch graduations, and others are placed proper distances apart to form fraction-of-an-inch graduations of predetermined 45 lengths.

A like notched rib, similarly placed, is located along the side of the triangle 11.

On the upper or outer face of the triangle 50 10 there are scribed parallel extension lines 10 registering with the walls of the notches 16. These lines are numbered 0, 1, 2, 3, 4, 5, 6, and coincide with one of the perpendicular walls of each of the said notches which are 55 one inch apart, forming one inch divisions and designating the one inch graduations.

These numbered lines are called base lines. Shorter similar lines, similarly located with respect to the notches that are less than one inch apart, form fraction-of-an-inch divisions of predetermined lengths. These shorter lines, and the dimension lines 15 designate the fraction-of-an-inch graduations. For brevity the fraction-of-an-inch graduations are called minor graduations. For clearness 60 some of the short dimension lines are not provided with arrow heads.

The one inch divisions are successively contiguous in a straight line so that the distance from the outer limit of the first division to 70 the outer limit of the 6th on the triangle 10 is six inches.

On or alongside the dimension lines 15 are placed figures denoting the lengths of the graduations. For brevity these lines are 75 called graduations. The lines bearing the fraction $1/3$ are, therefore, $1/3$ of an inch graduations; and it is obvious that if finger 23 on triangle 11 be properly inserted in the notch at one end of a $1/3$ inch graduation and a line properly scribed, then in the notch at the other end of it and a line scribed, the two lines will be $1/3$ of an inch apart.

Graduations less than, equal to, or only slightly longer than the width of the finger 85 23, are necessarily formed by means of one notch, the width of which is just equal to the width of said finger plus the length of the graduation. To illustrate, and referring to Figure 4, say that the width of the finger is 90 $1/16$ of an inch, then in case of a $1/16$ graduation the distance from the finger to the confronting wall of the notch in which it is positioned, is just $1/16$ of an inch, and if the finger is made to contact with the said wall, 95 triangle 11 will have moved just $1/16$ of an inch, as shown in Figure 4. The width, therefore, of a notch forming a $1/16$ inch graduation, is $1/8$ of an inch. Obviously, the width of a notch forming a $1/32$ inch 100 graduation is $3/32$ of an inch; $1/16$ inch for finger and $1/32$ inch for its movement within the notch.

The finger 23 is formed on a plate 22 that is riveted or otherwise secured to the angle 11, the said plate 22 having at its corners projections 24 arranged parallel with but of a less width than the finger 23. These projections provide the guards.

The extension lines, the arrow-headed dimension lines and the figures accompanying the same, as scribed on plates 10, 11 and 35,

form graduation charts 18. These charts can be printed upon suitable material and cemented to the plates.

As is well known, if an inch be divided into two parts, each part is a complement of the other, and if division is made as herein set forth, each can be used for laying off a distance; and, furthermore, one end of each graduation will rest on a one inch base line.

10 If one end of a graduation rests on a base line and there is another one-inch line properly located with respect to the one on which the graduation rests, said graduation plus an inch, can be laid off with but one shift of the 15 scribing plate as will be described further on.

It will be seen from an inspection of plate 10, Figure 1, that graduations formed in the above complementary manner, equal in length to odd multiples of a graduation unit, 20 can be located in one one-inch division, and those, equal in length to even multiples of said unit, located in another. For example: In the division between lines 3—4, the graduation unit is $1/16''$ and graduations consisting of multiples thereof, placed therein, are equal in length to odd multiples, only, of $1/16$. The graduations equal in length to the even multiples of $1/16$, viz: $1/8$, $1/4$, $1/2$, and $3/4$ are formed in the division 5—6. The 25 complementary feature is not shown or availed of in making the 96ths'' and 64ths'' graduations and their location is arbitrary.

The notches on one side of the triangle 10, forming minor graduations, are arranged 30 versely with respect to the juncture of the perpendicular sides of the said triangle. For example, on side 12 of the triangle 10, take notch $1/12$; this forms a $1/12$ inch graduation. It abuts on base line 0, while notch $1/12$ 40 on side 13 of the triangle abuts on line 1, which is nearer the right angle of said triangle than is line 0.

By reason of this feature there is always, 45 on one side or the other of the two short sides of the triangle, a base line just one inch distant from the one on which a graduation rests or abuts and is so located with respect thereto that any graduation, plus an inch or inches can be laid off on the paper with but one shift 50 of the scribing plate. For example, suppose the draftsman desires to lay off $1\frac{2}{3}$ inches and then add $1\frac{1}{3}$ inches to it having found from an inspection of index similar to the one on triangle 11 and of the graduations on triangle 10, that notches $1/64$ and $11/96$, and $10/96$ and $3/32$ are, respectively, at the termini of the desired $1\frac{2}{3}''$ and $1\frac{1}{3}''$ distances, 55 he will insert finger 23 in notch $1/64$, side 12 of triangle 10 and scribe a line along the long side of triangle 11, then, holding triangle 10 in place, insert finger 23 in notch $11/96$ and inscribe a line, the two lines will be just $1\frac{2}{3}$ inches apart. Now holding triangle 11 in place, he will turn triangle 10 so that side 13 60 will take the place that side 12 occupied, and

engage notch $10/96$, on said side 13, with finger 23, then, holding triangle 10 in place, insert finger in notch $3/32$ and scribe a line; it will be just $1\frac{1}{3}$ inches below the line above it.

70 Triangle 11 bears an index 33 containing a partial list of the graduations on chart 18. This index may be printed on suitable material and cemented to the upper faces of the triangles and consists of a block having four 75 columns; in the first of which there are arranged consecutively figures denoting the $1/32$ inch graduation and odd multiples thereof with their complementary graduations to the right. In the second column there are two columns of figures. They correspond 80 to those with which the base lines on chart 18 are numbered and they indicate, on triangles 10 and 11, the two lines between which a graduation is located. For example, the line of figures $1/32$, $31/32$, $3:4$, as arranged at top 85 of columns 1 and 2, indicates that graduations $1/32$ inch and $31/32$ of an inch are located between the base lines 3 and 4 on the charts. The draftsman, therefore, can tell by a glance 90 at the index just where on the plate, a desired graduation is located, and is able to rapidly lay off on the paper any graduation, within the scope of the device, with but little or no more tax on the mind and on the eyes than is involved in the use of a section liner, and to 95 make scaled drawings as he scribes the construction lines thereof, no previous recourse to any rule, whatever, is necessary.

100 The base lines are consecutively numbered toward the intersection of the charts, hence, the one-inch division between the lines 5 and 6 is common to both charts and bears graduations pertaining to each side of triangle 10. The plates 10 and 11 may be provided with 105 adjustable fingers on their upper or outer faces arranged so that they will not project beyond the edges of the plates when not required for use and whereby the said edges may be employed in scribing. The adjustable finger 26 on the plate 11 is carried by a block 27 that is slidable in a housing 28. The block has on its rear end a threaded extension 29 that passes through the rear of the housing and the housing is slotted for 110 the reception of a milled nut 30 that is screwed on the threaded part 29. This construction is also disclosed by dotted lines in Figure 1 and is indicated by the numeral 34.

115 The plate 35, shown in Figure 7, is a rectangular parallelepiped. On it the minor graduations are grouped as near to the center of the plate as practicable, and have one inch divisions between them and each end of the plate. By this arrangement more contacting 120 surface is afforded between two cooperating plates than is sometimes possible if the graduation that is being used is located near one end of the plate. Furthermore fewer notches are required, hence cost of manufacture is 125 130

less. Nevertheless with it, any of the graduations expressed on plates 10 and 11 can be laid off with but two shifts of the scribing plate, and many of them with but one. The 5 numeral 20 in Figures 1, 2 and 7 illustrates an anti-slipping device to prevent accidental movement of the plates when they are being operated.

Having described the invention, I claim:

- 10 1. A drafting device for the purpose set forth, comprising a guiding plate having a notched rib on one face, adjacent and parallel to one of the edges of the plate, cut transversely to form notches abutting on extension lines connected by numeral bearing lines 15 perpendicular to said extension lines and designating the length of a graduation, and a second plate having an outstanding finger adapted to operate in any of said notches.
- 20 2. A drafting device comprising a right angled guiding plate having notches one inch apart, along two of its adjoining perpendicular sides, to form divisions one inch in length, constituting one inch graduations and having other notches intermediate these to form, within the said one inch divisions, divisions less than one inch in length, constituting fractional inch graduations, said fractional inch graduations, on one side of 25 the plate being located in reverse order to those of same size on the other side of the plate and a second plate having a finger adapted to engage in any of the said notches when the corresponding edges of said plate are brought into contact.
- 30 3. In a drafting device, a right angled guiding plate having, along two of its adjoining perpendicular sides, rectangular notches each having one perpendicular wall 35 coinciding with scribed lines on said plate one inch apart the lines on each side being numbered consecutively from the juncture of the said perpendicular sides, so that lines, on each side of the plate, equally distant from the said juncture, will bear the same numeral.
- 40 4. A drafting device for the purpose set forth, comprising a scribing plate having a notched rib on one face, parallel to one of the edges of the plate, a chart on said plate having graduation lines adjacent the notches connected by numeral bearing lines perpendicular to said graduation lines, and a second scribing plate, a finger thereon adjustable to be projected beyond the edge of the plate, and adapted to engage in any one of the notches of the rib when the corresponding plate edges are brought into contact.
- 45 5. A drafting device for the purpose set forth, comprising a guiding plate having notches along one of its edges, forming a plurality of one-inch divisions, constituting, in connection with extension lines scribed on the plate one inch apart, one-inch graduations, and having, within the said one-inch
- 50 6. A drafting device for the purpose set forth, comprising a guiding plate having an upstanding rib on its upper face, adjacent and parallel to one of its edges, having transverse notches, one inch apart, with one wall 55 of each coincident with an extension line, forming one-inch graduations, and, intermediate the said notches, other notches, each having one wall coincident with an extension line connected by perpendicular numeral bearing lines, forming, in a complementary manner, fractions-of-an-inch graduations located irregularly along the edge of the said plate the entire length of its notch-bearing portion, and a second plate having a finger 60 adapted to engage in any of the said notches.
7. A drafting device for the purpose set forth, comprising a guiding plate having, along one of its edges, notches, one inch apart, each having one wall coincident with extension lines, scribed on the plate, one inch apart, forming a plurality of one-inch divisions, to form one-inch graduations, and, within the said one-inch divisions, other notches having one wall coincident with extension lines connected by perpendicular numeral bearing lines, forming, in a complementary manner, fractions-of-an-inch graduations, of different sizes, located irregularly along the edge of the said plate the entire length of its notch-bearing portion, and a second plate having a finger adapted to engage in any of the said notches.
8. A draftsman's guiding plate containing, along one of its edges, one-inch divisions 70 formed by notches having a wall coincident with extension lines one inch apart, constituting one-inch graduations, and, within the said one-inch divisions, other notches and extension lines forming smaller graduations; 75 said smaller graduations equal in length to odd multiples of a graduation unit of a predetermined size being located in one one-inch division, and those equal in length to even multiples of the said unit being located in another of the said divisions.
9. A drawing apparatus comprising a right angled guiding plate, graduated by notches, having at the juncture of two perpendicular sides, a division common to both 80 of said sides; said division containing notch-formed fractions of an inch graduations designated by extension lines connected by numeral-bearing dimension lines scribed on the plate; and a cooperating plate provided 85 with a finger adapted to engage in any of the said notches.

In testimony whereof I affix my signature.

WILLIAM E. ELAM.
